ALBERT H. WADELL, OF NEWARK, NEW JERSEY

MACHINE FOR TRIMMING METAL PARTS

Application filed October 11, 1929. Serial No. 398,866.

This invention relates to an improved machine for trimming metal parts by turning or tooling the inner or outer circumferential surface thereof and is particularly constructed and adapted for use as a machine for finishing or refinishing brake drums.

The object of the invention is to provide a machine which receives one or two wheels which are rotated at selective speeds and are operated all together or independently and in which a tool traverses the drums on the wheels to provide a smooth surface on which the brake bands bear.

Another object of the invention is to provide a self-contained unit of this kind which needs only to be connected with a source of electric power and also one in which the supports for the wheels are relatively low in order to make it easy to place heavy truck wheels and the like on the spindles of the machine.

The machine is illustrated in the accompanying drawings in which Figure 1 is a side view of my improved machine and Figure 2 is a top view thereof. Figure 3 is a cross section of part of the machine and showing the driving mechanism of the tool holder and the spindles. Figure 4 is a section on line 4-4 in Figure 3 and Figure 5 is a section on line 5-5 in Figure 3. Figure 6 is a perspective view of a part of the gear shift.

The machine illustrated comprises a base 10 on which is secured the casing 11 which has a central compartment 12 for the inner ends of the spindles 13 which support and turn the articles to be tooled. The casing 11 also has the side tracks or rails 14 on which the tool carriages 15, are made to slide. The spindles 13 carry the articles such as wheels and brake drums and the tool carriages hold the tool shaft 16 which in turn hold the tools 17 which traverse the face such as the face 18 of the article shown at 19.

The machine is adapted to hold various sizes of wheels or bands and to be run at various and different speeds. That is, the wheels at both ends of the machine can be turned at slow speeds or one can be turned slowly and the other turned at higher speed accord-

ing to the requirements in each particular case.

The two spindles 13 are driven each by a gear connection, one connection consisting of a gear 20 on one of the spindles 13 and a gear 21 on the short shaft 22 and the other consisting of a gear 23 on the other spindle 13 and a gear 24 on the short shaft 25. The shafts 22 and 25 are connected by gears 26 and 27. The gear 27 is driven through a gear shift mechanism from the main shaft 28. The main shaft is driven by a motor 29 (see Figure 1) through the worm 30 and the worm gear 31.

The gear shift consists of a gear 32 slidable on the main shaft 28 and driven thereby. The gear 32 and the idle gear 33 are secured to the bracket 34 and are raised, lowered and turned by a handle 35 on the bars 36 of the bracket. The bars 36 operate in a slot 37 (see Figure 2) in the top of the housing 38 which covers the above described gear connections. The gear 33 can be swung to engage the multiple gear including gear 27 above mentioned or the gears 39 and 40 to vary the speed of the shafts 22 and 25. The gear 26 is connected at will to the shaft 25 by the clutch 40 operated by the yoke 41 and the shaft 42 and handle 43. The multiple gear is connected to the shaft 22 through the clutch 44 operated by yoke 45 on the shaft 46 and operated by handle 47. This mechanism provides for the selective operation and speed of the two oppositely extending spindles 13.

The carriages 15 which travel back and forth on the tracks 14 are driven normally by the screws 48 which are arranged to rotate in bearings in the casing and in the nuts 49 on the carriages 15. Each screw 48 is rotated by a gear 50 in mesh with a gear 51 on the shaft 52. The shaft 52 is coupled to a shaft 53 by the clutch 54. The shaft 52 has a longitudinal play and is provided with a hand wheel 55. When the wheel 55 and shaft 52 are pulled out to disengage the clutch 54, the carriage is moved by the hand wheel rotation. This is for adjustment of the carriage and its tool holder relative to the work. After adjustment is completed the clutch 54 is engaged and the tool operates on the work 100.

by reason of the rotation of the shaft 53 by gear wheel 56 in mesh with gear 57 on shaft 58 which is geared at 59 to the main shaft 28.

The carriage 15 includes a fixture 60 which is 5 slidable transversely on the tracks 61 by the screw 62 worked by handle 63. The fixture 60 is preferably provided with the holders 64 in either or both of which the tool bars 16 can be held by bolts 65.

10 It will be evident from this description and the drawings that the machines can be used to finish two brake drums at the same time, at selective speeds and in a short time. The utility of the machine will be apparent and 15 changes can be made in the various parts without departing from the scope of my invention.

I claim:—

20 1. A machine for trimming brake drums comprising a housing, a motor in the lower part of the housing, a pair of wheel-supporting spindles, one projecting from each end of the housing, mechanism enclosed in the upper part of the housing above the spindles, said 25 mechanism being connected to the motor and the spindles and including clutches operate the spindles selectively, and carriages mounted to slide at the sides of the casing, tool holders for carrying tools beyond the 30 casing for operation on wheels mounted on the spindles and a speed control device interposed in the said mechanism for controlling the speed of the spindles.

35 2. A machine for trimming brake drums comprising a housing, a motor in the lower part of the housing, a pair of wheel-supporting spindles, one projecting from each end of the housing, mechanism enclosed in the upper 40 part of the housing above the spindles, said mechanism being connected to the motor and the spindles and including clutches operate the spindles selectively, and carriages mounted to slide at the sides of the casing, tool holders for carrying tools beyond the 45 casing for operation on wheels mounted on the spindles, a speed control device interposed in the said mechanism for controlling the speed of the spindles and handles one on each clutch and one on the speed control device, said handles being arranged on the outside of the casing and at the top thereof to allow control from one point of the operation and speed of the spindles.

50 55 In testimony whereof I affix my signature.
ALBERT H. WADELL.
